UNITED STATES PATENT OFFICE.

FRANK TOTH AND KÁROLY GOMBOS, OF PHOENIXVILLE, PENNSYLVANIA.

CLOTHESLINE.

Application filed January 7, 1922. Serial No. 527,692.

To all whom it may concern:

Be it known that we, FRANK TOTH and KÁROLY GOMBOS, citizens of Hungary, residing at Phoenixville, in the county of Chester and State of Pennsylvania, have invented certain new and useful Improvements in Clotheslines, of which the following is a specification.

This invention relates generally to clotheslines, having particular reference to the supporting thereof.

The invention has for an object to provide a novel arrangement in which a single clothesline is stretched between facing walls, such as the walls of courts or light wells for use by different families.

Other objects relate to the adjustability of the supports for convenience in hanging clothes on the line, and to the locking of the line supports.

For further comprehension of the invention, and of the objects and advantages thereof, reference will be had to the following description and accompanying drawings, and to the appended claims in which the various novel features of the invention are more particularly set forth.

Fig. 1 of the drawings is a transverse vertical sectional view through the windows of opposed apartments, showing our improved clothesline in place.

Fig. 2 is a face view of the support, showing in face elevation a portion of the wall and window frame.

Fig. 3 is a top plan view thereof showing the wall in horizontal section.

Fig. 4 is enlarged fragmentary vertical section on the line 4—4 of Fig. 3.

In the embodiment of the invention herein set forth we mount on the wall 10, adjacent the window opening 11, a pair of vertically spaced rods 12 extending horizontally along the wall and fixed at their ends in brackets 13 rigid in the wall.

Upon these rods a crosshead 15 is mounted to slide freely and is formed with an angular pulley supporting arm 16 whose outer end projects across the window opening 11 when the crosshead is moved to the adjacent ends of the rods 12.

Suspended from this arm 16 is a horizontal pulley 17 having serrations or notches 18 closely spaced around the periphery thereof and with the intervening walls 55 tapered to wedge shape as at 19.

Formed integral with the pulley 17, on

the top face thereof, is a disk projection 20 having undercut notches or recesses 21 spaced around its periphery and adapted to be engaged by a locking device whereby the pulley may be held against rotation.

We also provide means to lock the crosshead 15 on the rods 12 and preferably arrange this locking means so that it can be operated independently of, or in conjunction with, the pulley locking means.

To this end we provide a dog 23 hinged between its ends as at 24 on the crosshead arm 16 and having one end projecting through a slot 25 in the crosshead 15 and adapted to bite against the adjacent rods 12 when the dog is swung to approximately vertical position with respect to the rod.

Connected to the opposite end of the dog 23 is a link 26 which extends along the crosshead arm 16 and is connected to a locking arm 27 mounted on the end of crosshead arm and adapted to have one end laterally offset as at 28 to engage the notches in disk 20, the opposite end being in the form of a handle 29. The arm 27 is adapted to have both swinging and longitudinal movement into and out of engagement with the notched disk 20 and to this end it is mounted by means of a pin 30 carried by a pair of ears 31 projecting from the part 16, this pin projecting through a longitudinal slot 32 in the arm 27.

We preferably arrange the clothesline, as shown in Fig. 1 of the drawings, extending between two facing apartments to be used by the occupants of either apartment as desired, the wall of each apartment having one of the above described supports mounted thereon, the line being indicated at 35 as looped around the pulleys 17. When clothes are to be hung on the line, the locking arm 27 is swung to release the dog 23 from rods 12 and the crosshead 15 is moved along the rods 12 to bring the pulley 17 in front of the window opening 11. The clothes are then hung on the line, the construction of the pulley enabling the clothes to pass therearound, the pins being accommodated in the recesses 18, so that both reaches of the line may be used. After the clothes have been hung on the line the arm 27 is swung to lock both the pulley 17 against rotation and the crosshead 15 on the rods 12. Use of the line by the person in the opposite apartment is thus prevented until the line is freed. When the clothes are to be

- removed, the pulley 17 is freed, and after the clothes are removed the crosshead 15 is shoved back along the rods 12, withdrawing the pulley from in front of the window.
- 5 The arm 27 is raised until its end 28 is above the disk 20 and then swung to lock dog 23 to the rods 12, holding the crosshead 15 against movement but allowing the pulleys to rotate freely, permitting subsequent use of
- 10 the line by either party, the end 28 of arm 27 resting freely on the disk 20.

Having thus described our invention what we claim as new and desire to protect by Letters Patent of the United States is as

15 follows:

1. In a device of the class described, a pulley adapted to have a clothesline looped therearound, a support on which said pulley is movably mounted to permit of positioning 20 the pulley in front of or to one side of a window opening, means for locking said pulley to said support, means for locking said pulley against rotation, connecting means between said locking means, and a 25 handle adapted to operate said connecting means.

2. In a device of the class described, a pulley adapted to have a clothesline looped therearound, a support having a pair of 30 vertically spaced parallel rods on which said pulley is slidably mounted to permit of positioning the pulley either in front of or to

one side of a window opening, and a hinged dog adapted to bite against one of said parallel rods to lock said pulley in adjusted 35 positions on said support.

3. In a device of the class described, a pulley adapted to have a clothesline looped therearound, means for locking said pulley against rotation, a support for said pulley 40 comprising a crosshead and parallel rods carrying said crosshead, and means having unitary operation with the pulley locking means for locking said crosshead to one of said rods.

4. A support for a clothesline comprising a pair of vertically spaced horizontal rods, a crosshead slidable on said rods, an arm rigidly projecting from said crosshead, a pulley suspended from said arm and provided on its upper face with a disk-like projection having undercut notches in its periphery, a locking arm hinged to the first mentioned arm and having an offset end adapted to engage in said undercut notches, 55 a dog hinged to said first mentioned arm and adapted to bite against one of said rods, and a link connecting said dog and locking arm.

In testimony whereof we have affixed our 60 signatures.

FRANK TOTH.
KAROLY GOMBOS.
